UNITED STATES PATENT OFFICE.

EDWARD MASON, OF DETROIT, MICHIGAN, ASSIGNOR TO JOHN O'CONNOR,
OF SAME PLACE.

AUTOMATIC ADVERTISING DEVICE.

SPECIFICATION forming part of Letters Patent No. 323,176, dated July 28, 1885.

Application filed July 23, 1884. (No model.)

To all whom it may concern:

Be it known that I, EDWARD MASON, of Detroit, in the county of Wayne and State of Michigan, have invented new and useful Improvements in Automatic Advertising Devices; and I do hereby declare that the following is a full, clear, and exact description thereof, reference being had to the accompanying drawings, which form a part of this specification.

This invention relates to certain new and useful improvements in advertising devices, the object of the invention being to produce a device designed to be attached to a window and to tap upon the window-pane, so as to attract the attention of passers-by; and to that end the invention consists of a suitable hammer arranged to be operated intermittently or otherwise by a train of gear driven by a spring, all as more fully hereinafter set forth.

Figure 1 is a front elevation of my improvement, with one of the plates of the frame removed and attached to a window-sash. Fig. 2 is a side view of the same. Fig. 3 is a horizontal section through the line $x-x$ of Fig. 2.

In the accompanying drawings, which form a part of this specification, A represents a suitable frame-work, within which the operating parts of my device are located, and in which the main shaft B is journaled laterally, such shaft carrying the main spring C and the main driving gear D—such as is usually employed in clocks. This gear-wheel D meshes with a pinion, a, upon the shaft E, which also carries a gear-wheel, F, which latter meshes with a pinion, b, upon the shaft G, which also carries a gear, H, which in turn meshes with a pinion, c, upon the shaft I. Upon this shaft I is secured a sprocket-wheel, J, which meshes with the worm-shaft K, which is vertically stepped between the brackets d, such worm-shaft having secured near its upper end a balance-wheel, L.

Upon the shaft G is rigidly secured a crown-wheel, M, which meshes with a pinion, e, upon the horizontal shaft N, properly journaled in the ends of the brackets F'. Upon this horizontal shaft is rigidly secured a mutilated escapement, O, which projects through a slot in the adjacent wall of the frame, and in its rotation operates the verge P, the shaft of

which is journaled horizontally between the brackets g.

To the shaft of the verge is secured one end 55 of a curved arm, R, the opposite and free end of which carries a hammer, S, such hammer projecting beyond the front face of the frame.

In practice this device is secured to the window-sash by any convenient means in such 60 a position that the end of the hammer will, in the operation of the device, lightly come in contact with the glass T of a window-sash, U. I prefer to provide the frame with ears V, by which the device may be attached by screws 65 or otherwise to the sash U, as plainly shown in Fig. 1. The spring being wound up, it imparts motion to the train of gear herein described, causing the teeth of the mutilated escapement to operate the verge and the hammer, causing the latter to intermittently tap upon the window-pane, attracting the attention of those passing, who naturally would stop to inspect the device, while at the same time the wares of the merchant displayed in 75 the window for sale would be brought to their notice.

What I claim as my invention is—

1. An advertising device provided with means for attaching it to a window-sash, and 80 with a hammer and actuating mechanism, substantially as described, for causing said hammer to tap upon said window, as and for the purposes specified.

2. In combination with a window, a clock-work provided with a striking device for producing a tapping upon the window, substantially as and for the purpose described.

3. In combination with a window, a clock-work provided with a striking device for automatically producing an intermittent tapping upon said window, as and for the purpose specified.

4. In an advertising device, the combination of the window and window-pane with 95 the shaft G, shaft I, wheel J, worm-shaft K, balance-wheel L, shaft N, escapement O, verge P, arm R, and hammer S, arranged to be automatically operated by a train of gear and a spring, substantially as and for the purposes 100 specified.

Witnesses: EDWARD MASON.

JNO. REID SUTTON,

W. HENDRIK.
